RECORD HOLDER

Stanley T. Handel, New York, N. Y., assignor to
The Verplex Company, Essex, Conn., a corpora-
tion of Connecticut

Application July 16, 1941, Serial No. 402,660

6 Claims. (Cl. 211—40)

This invention relates to a holder for phonographic records of the disc type.

The general object of the invention is to provide a simple and inexpensive frame member having a plurality of compartments arranged within the frame, in combination with indexing means positioned at each compartment, whereby individual records may be stored away in identified position and readily removed as desired.

A feature of the invention covers the use of wire elements formed to provide a strong holder wherein a large number of records may be compactly held in such manner that any of them may readily be removed without substantially disturbing the others.

Another feature provides a supporting platform made of wire or the like at each of a plurality of positions in the frame member, each platform cooperating to hold a designated number of records with the result that the weight of the records is apportioned and distributed throughout the frame, and the total weight per compartment held to a predetermined maximum.

Another feature of the invention provides for forming the frame member so that it may easily be deposited within a protecting receptacle and lifted therefrom when required.

Another feature covers the provision of means for removably positioning cover and separating mats which serve to protect adjacent records from rubbing against each other while at the same time providing suitable support and identification for records resting thereon.

Other objects and features will be more apparent from the following description of one form of the invention to be read in connection with the accompanying drawing in which

Fig. 1 is a perspective view of a frame member designed to house and identify records, in accordance with the invention;

Fig. 2 is a fragmentary view of one of the supporting wire platform elements on which a record is shown supported on one of a group of identifying cover and separating mats;

Fig. 3 is a detail view of a pack of cover and identifying mats positioned on one of the wire supporting platforms within the frame member;

Fig. 4 shows a plan view of the pack;

Fig. 5a is a view looking at the front of the pack, whereas Fig. 5b is a view looking lengthwise of the pack, and;

Fig. 6 shows a container adapted to house a loaded frame.

Considering the drawing, similar designations referring to similar parts, numeral 7 designates

a circular wire element. While element 7 may be of different form, it is preferably circular when the frame, generally designated by the numeral 8, is used to house records. Element 7, as well as the others making up the complete frame are of wire of suitable gauge to provide a rigid yet lightweight structure. Element 9 provides two upright legs 14, 15 suitably secured to 7 at points 10 and 11, and intermediate cross bar 12 which is formed at central portion 13 to provide a handle for the complete assembly.

A plurality of support bars 16 have their ends suitably secured as by spot welding to legs 14, 15. Support bars 16 are preferably horizontal in position.

Rear upright wire support elements 17, 18 are secured to 7 at points 19, 20 respectively. Elements 17, 18 have their upper ends bent at points 21, the upper extremities being secured to cross bar 12 respectively at points 22, 23.

Wire support platform elements 24 are positioned at each support bar, being secured thereto at points 25. Elements 24 are in the form of a U, the closed end of the U projecting beyond support bar 16, the ends of the legs of the U being secured to upright support elements 17, 18 respectively at points 26, 27. The legs are secured at points 25 substantially midway of their length, with the result that the U portion protrudes beyond support bar 16, with the enclosed portion of the U 28 substantially positioned above and in line with the periphery of element 7.

Points 26, 27 are somewhat below the level of points 25, so that the complete platform element 24 tilts back and downwardly. Records placed upon the platform element will therefore be secured against slipping out of the frame. The tendency will be for them to slide back.

Proximate points 26, 27, each platform element 40 is provided with two upright wire guide elements 29. These may be rubber covered or otherwise suitably protected to prevent damage to records and so that index mats or cards fitted thereover will not have the perforations in which the guides fit, subject to undue abrasion.

Numeral 30 represents a group of cover and separating mats, fitted on a platform element 24, each of the mats having perforations 31 adjacent their rear edges, the mats being slipped over guides 29.

The frame may have five or more compartments, depending upon the number of support bars 16 and platform elements 24. On each platform element, a pack of mats will be positioned.

Fig. 4 shows the upper covering mat or top

master sheet at the front edge of which are a series of numbers in the nature of an index. The records housed within the pack of mats will bear numbers corresponding to those on the top mat. Thus, for example, if the top mat bears numbers one to ten as indicated in Fig. 4, then records numbered one to ten will be held within this pack. The records may be numbered by suitable pasters or inscriptions. In Fig. 5a, an end view of the pack looking directly at the front of the frame shows how the front edge for a distance of approximately a half inch back from the front will be cut away. The side view of the same pack is shown in Fig. 5b wherein it may be noted that element 24 supports the pack; the bottom mat 32 is entirely cut away for about a half inch from the front edge E while the others all extend to the front edge except that tab portions are cut away, but only for a distance of about a half inch back from edge E to present an appearance as illustrated in Fig. 5a.

To load records, the thumb or other lifting finger is placed at the number corresponding to the number of the record which is desired to load or subsequently to remove. For example, to open the mat for record 6, the finger lifts the pack at point 6 and every mat above mat 6 will be lifted. The same process is employed for any other designated record. When record 1, in the group illustrated in Fig. 4, is desired all of the mats will be lifted by lifting at point 1 with the exception of the bottom mat 32. Thus, only the top master mat need be marked, while the mats beneath, which may be considered divider mats positioned between or dividing adjacent records, require no printing. In practice the top mat bearing the markings will not become soiled since normally the top surface will not be touched when operating the mats.

The mats slide up and down upon guides 29 so that no binding takes place. Each of the mats may be made of paper or other desirable material for presenting a protecting surface between adjacent records.

The frame when loaded, or otherwise, may be lowered within a receptacle such as 33 shown in Fig. 6 equipped with cover 34 to make it substantially dust proof. Thus, the frame may be easily placed within and lifted out of such a receptacle without breakage or disturbance of the records retained in their respective positions.

Since many changes may be made in the invention without departing from the scope thereof, it is intended that all matter set forth in the foregoing description, or shown in the accompanying drawing, be regarded as illustrative only and not in a limiting sense.

I claim:

1. A record holder of the character described, comprising an annular wire base member, an inverted U-shaped member having a cross-bar from which a pair of legs depend and are secured to opposite sides of the base member, other cross-bars arranged below the first mentioned cross-bar and having their ends secured to said legs, a pair of inverted L-shaped upright members spaced a less distance apart than said leg members and having upper ends secured to the first mentioned cross-bar and their lower ends secured to the base member, and recumbent U-shaped platform members having curved front

portions protruding beyond said legs, each platform member having legs secured to one of the second mentioned cross-bars and to said rear upright members, the legs of each platform member being spaced apart a distance substantially equal to the distance between said rear upright members.

2. A record holder of the character described comprising a circular base member, an inverted U-shaped upright intermediate member formed of a single wire element and having ends secured to the base member, a pair of inverted L-shaped rear upright members joined at their upper ends to said element and at their lower ends to said base member, a plurality of platform members joined to said rear members, and means in combination with the intermediate members secured to the platform members.

3. In a record holder of the character described, a curved loop wire base member, a second wire member having two legs and a cross bar integral with each other, said two legs being secured to the base member, a plurality of platform members each substantially in the form of a U and means in combination with the legs for securing the platform members to the legs at a plurality of points spaced from the base member, said platform members being adapted to retain in position thereon a plurality of discs, and means on the platforms for positioning retaining and identifying means between adjacent records.

4. A record holder of the character described comprising a first wire element substantially circular in form, a pair of upright wire members, each substantially in the form of an inverted L, the extremity of the long leg of each L being secured to the first wire element, a second inverted U-shaped element having the ends thereof secured to the first wire element and to the extremities of the short legs of each L and means secured to different points along each L and to said second element for retaining a plurality of records in superposed position, and means in combination with said last mentioned means for positioning a protective mat between adjacent records.

5. In a record holder of the character described an annular base element, an inverted U-shaped member having bars forming intermediate supporting elements and having lower ends secured to the base element, rear supporting elements connecting the base element and the upper portion of said U-shaped member, recumbent U-shaped platform members connected to said intermediate and rear elements, one portion of each platform element protruding beyond said intermediate supporting elements to provide support for a series of records, said platform members being inclined downwardly toward said rear elements so that the records tilt downwardly toward the rear elements when placed within the holder.

6. A record holder of the character described comprising a base element, upright elements connected to the base element, support bars connected to some of said upright elements, platform elements in combination with the support bars, guide means on the platform elements, and mats on said guide means adapted to receive disc records therebetween.

STANLEY T. HANDEL,
